UNITED STATES PATENT OFFICE.

AUSTIN F. JACKSON, OF TAUNTON, MASSACHUSETTS, ASSIGNOR TO THE REED & BARTON CORPORATION, OF SAME PLACE.

DESIGN FOR A SPOON, &c.

SPECIFICATION forming part of Design No. 20,787, dated June 2, 1891.

Application filed April 11, 1891. Serial No. 388,595. Term of patent 7 years.

To all whom it may concern:

Be it known that I, AUSTIN F. JACKSON, residing at Taunton, Bristol county, State of Massachusetts, have invented and produced 5 a new and original Design for Handles of Spoons, Forks, and Similar Articles, of which the following is a specification, reference being had to the accompanying drawing, forming part thereof, and in which the figure is a 10 face view of a spoon the handle of which is designed according to my invention.

The leading feature of my design consists in the representation upon the face of the handle of forget-me-nots encircled by a cord 15 tied in a loose knot.

The design includes the representation of forget-me-nots A and B, the former being larger than the latter, the cord C being shown

as encircling the upper larger forget-me-not A, knotted loosely at D between the representations A and B, and passed thence around the forget-me-not B, with its ends extending down the face of the handle. ²⁰

While the design is shown in connection with the handle of a spoon, it is manifest that ²⁵ it may be applied to forks, ladles, and the like.

Having thus described my invention, what I claim, and desire to secure by Letters Patent, is—

The design for the face of a handle for 30 spoons, forks, &c., as shown.

AUSTIN F. JACKSON.
